UNITED STATES PATENT OFFICE

ARTHUR W. HELMHOLTZ, OF HARRISBURG, AND DENT FERRELL, OF MARION, ILLINOIS

SEPARATION DEVICE FOR PIPE LINES

Application filed August 29, 1931. Serial No. 560,096.

This invention relates to improvements in a separable pipe line connection for a blasting cartridge and is particularly applicable for use in connection with apparatus used in a system of blasting such as disclosed in our former Patent No. 1,569,226 issued January 12, 1926.

As disclosed in our former patent, we employ a blasting cartridge consisting of a rigid container or shell having associated therewith a rupturable wall and having connected thereto, a pipe line from a source of pressure. The apparatus is used by placing the blasting cartridge in a drill hole and delivering to the blasting cartridge through the pipe line under high pressure an expansible gas whereby, when the rupturable pressure is reached, the gas is released from the blasting cartridge and expands in the material to be blasted thereby breaking down the material. As disclosed in our application Serial No. 551,085, filed July 16, 1931, construction may be used in which the pipe line connection is made to the same end as the rupturable wall whereby the reaction upon release of the blasting medium tends to hold the blasting cartridge in the drill hole.

In such a system it has been found that injury to the pipe line or its connection to the blasting cartridge may result, due to the breaking down of the material, and it is the purpose of the present invention to disclose a construction in which the pipe line connection may readily separate from the blasting cartridge without injury to any of the parts.

It is therefore an object of the present invention to provide a pipe line connection to a blasting cartridge whereby a high gas pressure may be delivered to the blasting cartridge without producing any tendency to separate or release the pipe line connection but arranged in such a manner that a tensile force tending to separate the pipe line from

the blasting cartridge will separate the parts without injury or by breaking a renewable part and making it relatively easy to again connect the pipe line to the blasting cartridge for another operation.

Further objects and advantages of the present invention will be more readily apparent from the following description taken in connection with the attached drawing, in which—

Figure 1 is a diagrammatic view illustrating the association of the blasting apparatus with a wall of material to be blasted;

Figure 2 is a longitudinal section of the releasable pipe line connection;

Figure 3 is a longitudinal section of a modified form of the pipe line connection, and

Figure 4 is a detail longitudinal section illustrating a further modification of the construction shown in Figure 3.

There is disclosed in Figure 1, a wall of coal 14 to be blasted, having an undercut 16 and a drill hole 18 into which is inserted a blasting cartridge 22 and having connected thereto, a pipe line 26 by a releasable connection 28. The blasting cartridge includes a rupturable wall 30 at its outer end and the remainder of the drill hole is filled by the tamping 32. It will be understood that a high gas pressure will be delivered through the pipe line 26 to the blasting cartridge until the rupturable pressure of the wall 30 is reached whereupon the gas will be released from the blasting cartridge and expand in the wall 14 of the material to be blasted, tending to break down the material. The blasting cartridge 22 will tend to remain in the drill hole without movement therefrom during the blasting. The pipe line 26, leads through the tamping 32, and being gripped tightly thereby, will tend to separate from the blasting cartridge when the material is forced away by the blast.

The pipe line 26, as shown in Figures 2 and 3, is protected by a flexible armoured

covering 34 and the releasable connection 28 which connects the pipe line 26 to the blasting cartridge 22 is so designed that a tensile pull will separate the pipe line from the blasting cartridge without injury to the parts, or in such manner that it is only necessary to insert a renewable part to make a new connection.

In Figure 2 the end of the pipe line 26 is flanged or beaded as at 36, and is clamped by 10 the nut 38 threaded into the tubular shell 40 against a sealing ring 42. A short tubular piece 44 is secured to the blasting shell 22 by the nut 46 threaded into the shell and clamping the beaded end 48 of the tube 44 15 against a sealing ring 50. The tube 44 is in communication with a passage 52 leading into the interior of the blasting shell. The tubular shell 40 is frictionally secured to the tube 44 by the provision of packing 54 received in 20 the shell 40 and compressed tightly against the tube 44 by the gland nut 56 which is threaded into one end of the shell 40.

It will be readily understood that by adjusting the nut 56, the force required to separate the pipe 26 from the pipe 44 by tensile pull, may be varied and in order to make a new connection it is only necessary to release the nut 56 to permit the reinsertion of the pipe 44 into the packing 54, whereupon the 30 nut 56 may be again tightened. Such connection will be gas-tight under the high pressures which may be developed, due to the fact that the length of the packing may be made as long as desired to secure a tight seal.

In Figure 3 we have disclosed a modified construction in which the pipe 26 extends into an opening 58 in a tubular member 60 and is beaded or flanged over its end as at 62 to engage a shoulder 64 of the member 60. 40 A ring 66 is pressed against the flanged end of the pipe 26 through adjustment of a nut 68 threaded into the member 60 which serves also to make a tight connection with the flanged end 70 of a short piece of tube 72. 45 The tube 72 is connected to the blasting shell 22 at its opposite end in a similar manner by a nut 74 threaded into the shell 22, which presses against the flanged end 76 of the tube 72 and forces the flanged end against a sealing ring 78.

With this form of connection, upon the release of the blasting medium from the shell 22, the movement of the material broken 55 down will place a tensile force upon the tube 72 and the beaded end at one end of the pipe 72 will finally fail and permit separation. In order to make a new connection it is only necessary to replace the tube 72. The tube 72 60 together with the nuts 68 and 74 make a unitary construction which may be made up for ready use when it is desired to connect the pipe line 26 to a blasting cartridge for another blasting operation.

55 In the further modification of Figure 4,

there is shown a pair of co-axially disposed nuts 68 and 74 having extending therethrough a tube 72 which is beaded at its end as at 70 and 76, all of which is similar to the arrangement in Figure 3. However, in this form, one of the nuts is formed with a socket 80 adapted to receive a projection 82 from the other nut. The nuts are therefore connected by a socket joint which prevents injury to the tube 72 which is preferably of soft material such as copper by lateral movement of the nuts. Therefore, during the handling of the releasable connection as thus made up, a shearing strain can not be subjected to the tube 72.

It is to be understood that many modifications may be resorted to without departing from the scope of the invention as expressed in the appended claims.

We claim:

1. In combination with a blasting cartridge adapted to have an expansible gas delivered to said cartridge under high pressure, a pipe line for conducting the gas under pressure to said cartridge, and a connection 90 between said pipe line and said cartridge releasable by a tensile pull upon release of the blasting medium from the cartridge.

2. In combination with a blasting cartridge comprising a rigid container and a rupturable wall, a pipe line for conducting gas under high pressure to said blasting cartridge whereby at a predetermined pressure the rupturable wall will release the gas from said cartridge, and a releasable connection 100 between said pipe line and said cartridge including a renewable part.

3. In combination with a blasting cartridge and pipe line for delivering gas under high pressure to said cartridge, a short tubular member forming a releasable connection between said pipe line and said cartridge, and a pair of nut members respectively, securing said tubular member at its ends to said cartridge and to said pipe line, whereby said tubular member is readily replaceable for again connecting the pipe line to the blasting cartridge after release of the connection due to a blasting operation.

4. A releasable connection adapted to connect a pipe line to a blasting cartridge, comprising a pair of nut members co-axially disposed, and a short tubular member extending through said nut members, said tubular member having beaded ends to retain said nut members against displacement whereby one of said nut members may be threaded into a blasting cartridge to secure said tubular member thereto, and the other of said nut members may be threaded into a pipe line to secure the other end of said tubular member thereto.

5. A releasable connection between a pipe line and a blasting cartridge, comprising a pair of co-axially disposed threaded nut

members, one of said nut members having a projection fitting into a socket in the other of said nut members for preventing lateral displacement, a renewable tubular member extending through said nut members, said tubular member being beaded at its ends to overlap the opposite ends of said nut members, whereby one of said members may be threaded into a blasting cartridge to secure one end of said tubular member thereto and the other of said members may be threaded into a pipe line to secure the other end of said tubular member thereto.

10 Signed at Marion, Illinois, this 25th day
15 of August, 1931.

ARTHUR W. HELMHOLTZ.
DENT FERRELL.
